Primary Examiner — Ricky Pham(57) **CLAIM**

The ornamental design for a chef's knife, as shown and described.

DESCRIPTION

FIG. 1 is a perspective view of the chef's knife showing my new design.

FIG. 2 is a left side view of the chef's knife showing my new design; and,

FIG. 3 is a right side view of the chef's knife showing my new design.

The broken lines showing the environmental structure of the chef's knife surrounding the indentation are for the purpose of illustration and form no part of the claimed invention.
